James E. A. Gibbs, of Mill Point, Va.
Letters Patent No. 1103. Dated May 7, 1859.

The Schedule referred to in these Letters Patent and making part of the same.

To all persons to whom these presents shall come:

Be it known that I, James E. A. Gibbs, of Mill-
point in the County of Pocahontas in State of Virginia, have invented or produced a new and
original design for a Casting of a Sewing Machine, and I do hereby declare that the said
new design is fully described and represented in the following specification and accompa-
nying drawing to which reference is hereinafter made -

The figure of the accompanying plate of drawings represents my new design,
being a side elevation or profile view of my sewing machine.

The main Casting or frame is essentially in the shape of the roman letter
G, being a ring open on one side and set on a base or pedestal tangent thereto.

At the part where the ring is open, it terminates at one end, i.e. the upper
end with upright guides through which the of the pressure pad and the needle bar
are to pass, the other end i.e. the lower end terminates into an upright standard for supporting
the table upon which the cloth rests.

The ring somewhat diminishes in thickness toward either ends; it has -
that part where it is thickest or thinnest, I apply the first when which the needle arm
has its vibratory place.

This needle arm is shaped precisely like the main Casting, with the ex-
ception of its near portion, which is so twisted as to afford a convenient connection with the
eccentric on the shaft.

Thus the general appearance of the machine will be that of the Roman let-
ter G, which not only stamps it with a peculiar character but is also exceedingly useful,
as it affords the most space for the Cloth or material to be saved of being turned and twisted -
under the needle & upon the table;

Having thus described my new design for a Sewing Machine Casting,
What I claim is:

The peculiar form & figure herein described and set forth as the design
for the casting of a Sewing machine representing essentially the Roman Letter G in profil.
